WASHING AND EXTRACTING LIQUIDS FROM
TEXTILESRex Earl Bassett, Jr., South Bend, Ind., assignor
to Bendix Home Appliances, Inc., Detroit,
Mich., a corporation of Delaware

Application June 14, 1937, Serial No. 148,042

2 Claims. (Cl. 68—207)

The present invention relates to an apparatus for washing and extracting liquids from textiles.

The primary object of the invention is to provide an improved apparatus whereby both washing and extracting processes are performed by a single mechanical operation in a single receptacle, thus eliminating the use of clutches, speed changing mechanisms and the like. Heretofore it has been common practice to utilize washing machines in which washing is performed according to one method, such as agitation by a mechanical oscillator or liquid currents and in which the extraction of liquid is performed by a centrifuging operation. The change from washing to extraction requires either transfer of clothes from one receptacle to another and a similar transfer of drive, a change in drive from oscillatory to rotary motion, or a change from one driven member to another. Even in machines having only a single receptacle used in both the washing and extracting processes a speed changing device has heretofore been used.

Another object of the invention is to provide an improved washing and liquid extracting machine having a minimum of mechanical parts and in which the change from washing to extracting is accomplished by manipulation of a single control means which does not, however, affect the mechanical operating parts of the machine.

A further object of the invention is the provision of a new and improved method of cleansing textiles and like goods which comprises the steps of alternately simultaneously lifting the goods from the liquid and compressing them and immersing and releasing them.

The apparatus embodying the invention includes a stationary tub-like receptacle preferably, but not necessarily, circular in shape and having therein a reciprocable perforated piston suitably operated by a connecting rod extending through the bottom of the receptacle. The upper end of the receptacle is open so that textiles may be inserted into a variable volume washing chamber defined by the lateral side walls of the receptacle, the top of the piston and a removable imperforate cover adapted to close the receptacle during the operation of the machine.

The receptacle is filled with liquid and soap suds or other detergent to a suitable height, preferably, but not necessarily, a height less than that occupied by the textiles when compressed by the piston. The piston is reciprocated at a fairly rapid rate alternately to compress and release the textiles. In the operation under preferred conditions, liquid is expressed from the textiles on the compression stroke and flows past the piston into the bottom of the receptacle, and on the release stroke the liquid is forced into the washing chamber. The above described operation of the reciprocable piston results in the al-

ternate immersion and lifting of the textiles in and out of the liquid, respectively. On the compression and lifting stroke the liquid is expressed from the textiles, and on the release stroke the textiles are released and immersed in the liquid. The textiles are thus subjected to a continuous and reversing flow of liquid therethrough that effectively cleanses them. The textiles are also effectively distributed over the entire transverse area of the washing chamber and are thus all equally acted upon by the liquid.

When the apparatus is operated with the receptacle substantially filled with liquid, the textiles are alternately compressed and released while immersed in liquid. The alternate compression and release creates a vigorous reversing flow of liquid through the textiles and thus effectively cleanses them.

The textiles may be rinsed by supplying a fresh supply of liquid to the receptacle and finally dried after withdrawal of liquid therefrom.

According to the preferred embodiment of the invention the washing operation is initiated simultaneously with the admission of liquid to the receptacle. The liquid admission ports are preferably located so that the textiles in the upper portion of the receptacle are wet first. In this manner the textiles are gradually wet from top to bottom, with the result that dirt particles float downward to the bottom of the receptacle.

While the above mentioned cover has been described as being imperforate, such construction is not essential to the practice of the invention, as will appear more fully hereinafter. Both the cover and piston or only one of them may be perforated. In case the piston is imperforate, then some other means of communication from the top side thereof to the bottom of the receptacle must be provided, as by grooves in the receptacle wall or communicating perforations therealong.

Other objects and advantages of the invention will become apparent from the ensuing description, in which reference is had to the accompanying drawings, in which:

Fig. 1 is a front elevation, partly in section, of an apparatus embodying the invention;

Fig. 2 is a fragmentary top view of the apparatus, with the outer cover removed;

Fig. 3 is an elevation, partly in cross-section, of a modified form of receptacle and reciprocating means that may be used in place of that shown in Fig. 1;

Fig. 4 is a view similar to that shown in Fig. 3 of a further modification of the apparatus;

Fig. 5 is a diagrammatic representation of an arrangement for changing rotary to reciprocating motion used with the above apparatus;

Fig. 6 is a wiring diagram of the electrical ap-

paratus used for controlling the devices illustrated in the preceding figures; and

Fig. 7 is an elevation, partly in section, of the controller used in the electrical system.

5 These specific drawings and the description thereof that follows are to disclose and illustrate the invention and are not to impose limitation on the claims.

In the apparatus illustrated in Fig. 1 an upright 10 cylindrical shell 10 is mounted upon casters 11 and is provided with an inturned flange 12 surrounding the upper end for supporting a removable outer cover 13. The cover merely rests upon the flange and is provided for the purpose of 15 preventing liquids from splashing outside the casting, but it does not need to be secured in an airtight manner. A substantially cylindrical tubeshaped receptacle 14, adapted to contain the liquid used in washing and rinsing, is fixedly 20 mounted at its bottom on the circular flange 15 suitably secured to the inner side of the shell 10. The receptacle is somewhat smaller in diameter than the shell and extends upward to engage the flange 12 to which it is attached as by welding. 25 There is thus provided an annular space 17 between the lateral side walls of the shell and receptacle.

Liquid is supplied to the receptacle through 30 an inlet conduit 18 having between it and a suitable source of liquid (not shown) an electromagnetic solenoid valve 19. The inlet conduit extends upward in said annular space to the upper portion of the liquid receptacle 14 and is provided with a nozzle 20 through which liquid 35 is sprayed into the receptacle. Liquid is drained from the receptacle through a drain conduit 21 somewhat larger in diameter than the inlet conduit. The drain conduit is also provided with an electromagnetic solenoid valve 22 which, like valve 19, is adapted selectively to be opened and closed in accordance with the desires of an operator or in predetermined timed sequence by an electrical controller 24 attached to the side of the shell 10 and provided with a manually 45 operable controller 26 with which is associated a suitable dial marked with the operations of washing, rinsing and extracting.

The admission of liquid to the receptacle is controlled by a float switch 26 adapted to be 50 actuated through a rod 27 connected thereto and having slidably mounted thereon a float 28. The float is adapted to engage spaced apart collars 29 mounted on the shaft and as it slides along the rod in response to variations in water level. 55 The float switch and its actuating mechanism are mounted in a liquid-tight container 29 connected to the interior of receptacle 14 by a relatively small sized passage 30 consisting of coincident apertures in the container and receptacle. The details of construction and operation of the various controls will appear more fully hereinafter.

A variable volume washing chamber 31 is 60 defined by the lateral side walls of the receptacle 14, an imperforate cover 32, and means such as a piston 33 provided with a plurality of perforations 34, and mounted for reciprocation in the receptacle for periodically varying the volume between the cover and piston. The cover 32 and piston 33 are covered with relatively thin layers 32' and 33' of resilient material such as soft rubber in order to avoid breakage of buttons or the like usually found 70 on textiles. The layers may be suitably bonded

to the cover and piston or secured thereto by rivets or the like.

The imperforate cover 32 is removably mounted in the receptacle so that the latter may be filled with textiles and is secured in a position above 5 the nozzle 20 by means of a bayonet joint defined by vertical and horizontal grooves 35 and 36, respectively, suitably formed in the inner walls of the receptacle. The cover is securely locked in place by lowering it in groove 35 and then rotating it in groove 36. It is also provided with a handle 37 so that it may be readily secured in place and removed for the insertion of textiles therebelow.

The piston 33 is mounted for reciprocation 15 within the receptacle in an apertured journal plate 39 located above the bottom wall of the receptacle and a hollow downwardly extending guide 40, both of which are secured to the bottom wall by suitable means such as rivets 41. 20 The piston is securely attached to a connecting rod 42 adapted to reciprocate in the journal plate 39 and guide 40 and is surrounded by suitable packing 43 to prevent the leakage of water therealong. The piston and connecting 25 rod are adapted to be actuated through a resilient means such as a helical spring 44 mounted within a hollowed out longitudinal chamber 45 in the latter. The spring is alternately compressed and released by a rack bar 46 reciprocable within the hollow portion 45 and provided with a pin 48 slidable in a pair of diametrically opposed grooves 49 provided in the connecting rod. Thus, as the rack bar is moved up and down alternately to compress and release 35 the spring, the piston is alternately forced up and down in the receptacle 14, thereby alternately compressing and releasing the textiles contained therein.

The rack bar 46 is provided with gear teeth 40 50 so that it may be reciprocated through a speed and motion changing device 51 driven by suitable means such as an electric motor 52. The motor is adapted to drive the speed and motion changing device 51 through shafting 53 45 and the latter is provided with a pinion 54 which is rotated in alternate directions by suitable gearing within the device 51.

The gearing within device 51 is of the type 55 illustrated in Fig. 5, but may be of any other well known construction. Referring now to Fig. 5, it may be noted that shaft 53 is adapted to drive a pinion 55, in turn adapted to drive a gear 56. The latter is provided with a pin 57 mounted off-center and adapted to drive a connecting 60 rod 58 connected to a pin 59 mounted on a sector gear 60. The latter in turn drives the pinion 54 driving the rack bar 46. It is apparent that rotation of pinion 55 in one direction imparts periodically reversed rotation of gear 54 and the latter in turn imparts a reciprocating motion to the rack bar 46.

In operation, the apparatus described above is adapted to be operated at a fairly rapid rate of speed, preferably such that the piston will 65 be reciprocated once every three seconds or less. To wash textiles the covers 13 and 32 are first removed and the space above the piston 33 filled with textiles. Thereafter, the cover 32 is locked in groove 36 and the cover 13 is also placed in 70 position. Liquid is then admitted into the receptacle through the inlet 18 and the motor 52 started. The motor reciprocates the piston through the speed and motion changing device 51, the rack bar 46 and spring 44. The supply 75

of water is cut off, under the preferred mode of operation, when the liquid reaches a height just below the piston when the latter is in its uppermost position. Thus, when the piston is in its uppermost position, the liquid in the textiles is expressed therefrom and falls into the space back of the piston through the apertures 34 and when the piston is in its retracted position the textiles are released and immersed in the liquid which flows to the upper side of the piston through perforations 34. There is thus provided a continuous alternate immersion of the textiles in the liquid and a simultaneous lifting out and compressing thereof.

Although it is preferred that the liquid level be below the uppermost position of the piston, the washing process may be carried on advantageously in the apparatus described with the receptacle substantially filled with liquid. When operating under the latter condition the textiles are alternately compressed and released while immersed in the liquid. On the compression stroke of the piston the textiles are squeezed and the liquid expressed therefrom. On the release stroke the textiles are loosed and immersed in the liquid which flows upwardly at a considerable velocity through the perforations on the piston.

After the completion of the washing process the liquid within the receptacle is drained through conduit 21 while the motor 52 is in operation. At this time there is performed a dual function of drainage and continued compression and release of the textiles. After all the water is drained out then the clothes are dried by the continued alternate compression and release to which they are subjected.

In Fig. 3 there is illustrated a modified form of receptacle cover and piston in which both the piston and cover are perforated. The piston 33 is provided with perforations 34 and a layer 33' of rubber just as the apparatus illustrated in Figs. 1 and 2. The cover 62 is provided with a layer 62' of rubber and otherwise is constructed somewhat similar to the cover 32, with the exception that it is provided with perforations 63 and vertical flanges 64 to give it added rigidity. It, like cover 32, is removably mounted within the receptacle and when in place rests just above the nozzle 20. The piston 33 is illustrated in its uppermost position, at which time it is just above the liquid level, in accordance with the preferred mode of operation, the level being indicated by reference numeral 65. The operation of the apparatus utilizing the modified construction illustrated in Fig. 3 is substantially the same as that of the apparatus previously described. However, in this embodiment of the invention some of the liquid in the textiles is forced upwardly through perforations 63 during the compression stroke of the piston. On the release of the textiles this water flows back down through the perforations 63 into the textiles. During the washing process the operation is practically the same as that of the apparatus of Fig. 1, but because of the perforations in the cover the extraction is not quite as rapid as that of the previously described apparatus.

In the modification illustrated in Fig. 4, the piston 66 is provided with a layer 66' of rubber, but made without perforations, whereas the cover is similar in construction to that described in Fig. 3, consisting of a cover plate 62 provided with a layer 62' of rubber, perforations 63 and flanges 64. Liquid is supplied to the receptacle through a nozzle 67 located above the cover plate 62. The

liquid thus admitted into the receptacle flows into the space below the cover plate and also below the piston through perforations 63 and grooves 68 formed on the inner surface of receptacle 14. Thus, as the piston 66 is reciprocated within the receptacle, the textiles are alternately compressed and released. During compression the liquid is forced from the textiles above the cover plate 62 through perforations 63 and in back of the piston through the longitudinal 10 grooves 68. On the release stroke the liquid above the cover plate flows back into the textiles through the perforations while the liquid in back of the piston is forced upwardly along the grooves and into the textiles or above the plate 62, and 15 then into the textiles through perforations 63.

In the performance of the washing operation in accordance with the preferred mode, the textiles are alternately compressed and released. During the compression stroke water is expressed 20 from the textiles and on the release stroke the textiles are immersed in the liquid forced into contact and through the textile fabrics by the piston. There is thus provided a single receptacle in which liquid is forced alternately from one 25 side of a piston contained therein to the other to alternately immerse the textiles and thus wash or rinse them. No change need be made in the change-over of the machine from washing to 30 drying except to drain the liquid from the receptacle. The apparatus described utilizes a minimum of mechanical parts and which, because of its rapid reciprocation and the predetermined pressure applied to the textiles, is capable of performing with great efficiency both the washing 35 and drying processes. Furthermore, the apparatus described above is therefore adapted particularly to automatic control, because of the slight amount of control required to make the 40 apparatus completely automatic.

The electrical control system employed with the apparatus is illustrated in Figs. 6 and 7. Referring first to Fig. 7, there is disclosed a housing 71 mounted upon a base 72 made of suitable insulating material. Mounted in the base are 45 concentric arcuate contact strips to be referred to specifically in the description of Fig. 6. The controller housing 71 fits into the upper end of casing 24 attached to the side walls of shell 10. A contact arm 73 is attached to a vertical shaft 50 74 and carries contacts 75, 76 and 77 which sweep along the upper edges of the arcuate contact strips. The vertical shaft 74 has its lower end pivoted upon a step bearing 78 fixed in the center of the base 72 and is driven at slow speed 55 in a clockwise direction by an electrical motor and reduction gearing (not shown) inside a casing 79 that fits into the upper end of the controller housing 71.

The upper end of shaft 74 extends through a 60 cover 80 on the top of the controller housing 71 and has fixed thereon the indicator 25. The driving connection between the reduction gearing and the shaft 74 is capable of slippage to permit the shaft to be rotated manually by means of the 65 indicator 25, the slippage being provided by a frictional drive between the shaft and a gear 81 mounted thereon loosely.

The electrical system may be connected with an electrical supply line by means of a plug 83, 70 71 and a lead wire 84 connects the contacts 75 to 77, inclusive, with one of the prongs of the plug. Associated with contact 75 is an arcuate strip 85 extending substantially all the way around a portion of the base and connected by conductors 76

86 and 87 to the control motor 88, connected in turn by conductors 89 and 90 to the other prong of plug 85. The control motor 88, which is a constant-speed motor of the type used in electric 5 clocks, is arranged in the upper part of the housing 71. It is arranged to drive the shaft 74 through the reduction gearing, one gear 81 of which is shown in Figure 7. Concentric with arcuate strip 85 and spaced therefrom are a 10 plurality of arcuate conductors 81, 82 and 93, all interconnected by conductors 94 and 95. These are all connected by conductor 96 to the solenoid of inlet valve 19 having in series therewith the normally closed float switch 26 connected directly to supply conductor 90.

A third series of arcuate conductors 97, 98 and 99 cooperating with contact 77, are also provided, these being connected in series by conductors 101 and 102 and in turn connected to 20 the solenoid of the outlet valve 22 through a conductor 103. The solenoid valve is in turn connected by conductor 104 to the supply conductor 90. The contact carrying arm 73 is normally in the position indicated in Fig. 6, in which 25 all the apparatus is deenergized and, consequently, the apparatus is in an inoperative condition. When the contact carrying arm 73 is moved in a clockwise direction either manually by indicator 25 or by a switch 105 adapted to connect 30 the control motor 88 as well as the main driving motor 52 directly across the supply conductors, the apparatus is started and will carry out automatically the predetermined washing, rinsing and 35 drying operations. However, it is apparent that the operator may rotate the contact carrying arm 73 to any of the positions whereby the apparatus will immediately carry out the desired function.

In order to effect automatic operation of the apparatus, the operator first places textiles in the receptacle, together with the proper quantity of soap which may have a bluing compound incorporated therewith. The operator thereafter closes switch 105 to energize the control motor 45 88 and the main driving motor 52. The control motor 88 actuates switch arm 73 and thereby contact 75 into engagement with the arcuate strip 85 to close a holding circuit for the motors, the motor 88 thereby continuing to rotate contact 50 arm 73. Simultaneously with the initiation of operation of the motors a circuit is closed across contact 76 and contact strip 91, thereby closing an energizing circuit for the solenoid of inlet valve 19 and admitting water into the receptacle 55 14. After the liquid therein reaches a predetermined level, the float switch 26 is actuated into its open position and the inlet valve closes. During all this time and continuing throughout the operation of the motors, the piston actuated 60 by the main motor 52 is alternately raised and lowered within the receptacle alternately to compress and release the textiles therein.

After a predetermined length of time contact 65 71 engages contact strip 97, thereby to close an energizing circuit for the solenoid of valve 22. The latter effects opening of the drain valve and the liquid within the receptacle is drained out at a rate greater than at which it may be supplied through the inlet conduit, as explained above. 70 When the liquid drains to a level below the level at which the float switch is actuated, then the inlet valve opens to admit clean water into the receptacle and thereby aid in the rinsing operation.

After another predetermined length of time the engagement of contacts 76 and 91 is terminated, to cut off the supply of water to the receptacle. However, during this period the drain valve remains open. After a further predetermined 5 length of time the drain valve is closed and the inlet valve opened upon disengagement of contacts 77 and 97 and engagement of contacts 76 and 92 occurring simultaneously. Thus, fresh water is supplied to the receptacle to rinse the 10 textiles contained therein. A predetermined length of time thereafter the contact 77 engages contact 98, thereby again to open the drain valve in obvious fashion. At this time liquid is being supplied to and drained from the receptacle to 15 rinse the textiles contained therein. After a predetermined length of time, contact 76 leaves contact 92 thereby interrupting the supply of liquid to the receptacle and the liquid is drained therefrom. After another predetermined length 20 of time contact 77 moves out of engagement with contact 98 and contact 76 simultaneously engages contact 93, thereby again to supply fresh liquid to the receptacle. After a predetermined length 25 of time the drain valve is opened and thereafter the supply of liquid terminated and the textiles are dried by continued alternate compression and release. After the textiles have been thoroughly dried, contact 71 moves out of engagement with contact strip 99 thereby automatically terminating 30 35 operation of the machine.

While only a single washing operation and two rinsing operations have been described above, it is apparent that these numbers may be varied as desired. In some cases it may be desirable 40 to increase the number of washing operations and in other cases it may be desirable to either increase or decrease the number of rinsing operations. The control described above may be readily modified to meet these various requirements. 45

In the course of the above description, the word textiles has been used to describe the materials usually washed. It should be understood that this term has been used in its most generic sense and to cover all types of goods that may be 45 washed, cleansed or otherwise treated by a liquid, with or without a suitable detergent.

I claim:

1. Cleaning apparatus comprising an outer shell, a tub supported within and spaced from the shell at the upper end thereof, a vertically-reciprocable washing member in said tub, means within said shell below the tub for reciprocating said member, a drain from the bottom of the tub, and an inlet connection in the space between the shell and said tub having a nozzle discharging into the tub.

2. Cleaning apparatus comprising an outer shell, a tub supported within and spaced from the shell at the upper end thereof, a vertically-reciprocable washing member in said tub, means within said shell below the tub for reciprocating said member, a drain from the bottom of the tub, an inlet connection in the space between the shell and said tub having a nozzle discharging into the tub, a chamber containing a float and which communicates with said tub and which is arranged in the space between the tub and said shell, and control means for the inlet connection which is operatively controlled by said 70 float and which shuts off said connection when the float reaches a predetermined level.

REX EARL BASSETT, Jr.
